United States Patent Office

Des. 180,818
Patented Aug. 20, 1957

180,818

PULL

La Verne E. Clayton, Rockford, Ill., assignor to Amerock
Corporation, a corporation of Illinois

Application June 9, 1955, Serial No. 36,435

Term of patent 14 years

(Cl. D10—8)

Fig. 2 is a front view.

Fig. 3 is a sectional view taken along the line 3—3 in Fig. 2.

Fig. 4 is a perspective view of the pull.

I claim:

The ornamental design for a pull, substantially as shown.
